UNITED STATES PATENT OFFICE.

LORENZO JOHNSON, OF LOUISVILLE, KENTUCKY.

MACHINE FOR BENDING WOOD.

Application filed January 22, 1924. Serial No. 637,808.

To all whom it may concern:

Be it known that I, LORENZO JOHNSON, a citizen of the United States, residing at Louisville, in the county of Jefferson and 5 State of Kentucky, have invented a new and useful Machine for Bending Wood, of which the following is a specification.

This invention relates to wood bending as it is performed by a machine of the type in 10 which the wood strips are advanced into or between the shaping devices by rotating feed rolls, between which the strips are held.

Hitherto in bending wood, it has been customary to wet or steam the wood either 15 before or during its course through the machine. This necessitates drying the wood again, and not only does it require considerable time, but causes the wood to check and the surface to become rough, and 20 this together with the variations in the grain of the wood results in the production of many defective pieces which have to be discarded.

One of the important objects of the present 25 invention is to eliminate the time and expense incident to the moistening or steaming and subsequent drying of the wood, as well as the waste of material occasioned by the production of defective 30 pieces. This object is accomplished by the simultaneous application of dry heat and pressure to the wood through the feeding rolls and forming roll, so that the wood becomes seared or annealed, and at the same 35 time toughened and pressed into the desired shape without causing lateral expansion or swelling of the fibres, or other results which affect the strength or cohesive qualities of the wood, or its outward appearance.

Another important object of the invention 40 is to provide improved means for adjusting the machine for acting upon strips of different thickness, and for adjusting the former or shaping device so as to impart 45 any desired curvature to the wood and with any desired pressure.

The invention consists further in various 50 details of construction and novel combinations of the same, which will be more fully set forth in the following detailed description taken in connection with the accompanying drawings, which show the preferred form of the invention.

In the drawings:

Figure 1 is a side elevation of the machine, with parts thereof broken away and shown in section. 55

Figure 2 is a vertical longitudinal section through the machine.

Figure 3 is a view, partly in section and 60 partly in elevation, looking from the rear of the machine.

Figure 4 is a detail sectional view illustrating the means for adjusting the former.

Figure 5 is a sectional view taken on the 65 line 5—5 of Figure 4.

Figure 6 is a sectional view taken on the line 6—6 of Figure 4.

Figure 7 is a detail perspective view of the adjusting cam, and means for effecting 70 the adjustment.

Figure 8 is a side elevation of a former, which is interchangeable with the former shown in detail in Figures 4 to 7.

Figure 9 is a rear elevation of the former 75 shown in Figure 8.

Figure 10 is a vertical longitudinal section of the same.

Figure 11 is a section taken on the line 80 11—11 of Figure 10.

Figure 12 is a side elevation of a former which is interchangeable with those shown in the previous figures.

The machine is mounted on a suitable 85 frame 10, and the operating mechanism thereof is driven from a main power shaft 11 journaled transversely in the lower portion of the frame and provided with a drive pulley 12, or other suitable means for furnishing power. A counter shaft 13 is journaled in the frame 10 above the shaft 11, and provided with one or more spur gears 14, which are driven by similar gears 15 secured to the shaft 11. It may be stated 90 here, that for the sake of smoothness in the operation of the machine, I prefer to provide duplicate driving mechanism throughout the machine at each side thereof, as shown in the drawings, but it will be obvious 95 that the machine will be operative with only 100 one set of driving mechanism.

The machine is provided preferably with two pairs of feed rolls, the lower rolls 16 and 17 being secured to the respective shafts 18 and 19, which are journaled in the sides 105 of the frame 10, and provided at each end with the spur gears 20 and 21 operated in unison by the gears 22 which are carried

by a shaft 23, and operatively connected to the respective driving gears 24 secured to the ends of the shaft 13.

The upper feed rolls 25 and 26 are secured to the respective shafts 27 and 28, which are provided at each end with gears 29 and 30 connected by intermediate gears 31, which are secured to the shaft 32. The shafts 27, 28 and 32 are journaled at each end in a block 33, which is mounted for vertical adjustment in a recess 34 in the side of the frame, whereby the upper rolls 25 and 26 may be adjusted as a unit toward and from the lower feed rolls, in order to accommodate wood strips of different thickness. For the purpose of effecting this adjustment, vertical adjusting screws 35 are threaded into the blocks 33, and are provided at their upper ends with miter gears 36 in mesh with similar gears 37 secured to horizontal shafts 38, which are journaled within a housing 39 extending across the top of the frame 10, and provided at one end with hand wheels 40, or other suitable means for rotating the same to effect the adjustment.

The gears for driving the upper rolls are driven from the gears 41 secured on a shaft 42, which in turn are driven from gears 43 secured to a shaft 44 and in mesh with the gears 20. When the blocks 33 are adjusted, however, to adjust the upper feed rolls, it will be noted that the distance between the gears 29 and gears 43 will be increased or diminished, and for this reason means are provided for disengaging the gears 41 from the gears 29 and adjusting the same toward and from the same tangentially to the gears 43. For this purpose, the shaft 42 is journaled in blocks 45, which are slidably horizontally within the recesses 46, and shown in Figure 2, and adjusting screws 47 are swivelled at their inner ends to the blocks 45 and in threaded connection with plates 48, which are secured by any suitable means to the front end of the frame in front of the recesses 46 and covering the same. Suitable hand wheels 49 may be secured to the outer ends of the screws 47 for adjusting the same.

A forming roll 50, preferably larger than the feed rolls, is journaled in rear of the latter with its lower surface substantially in horizontal alinement with the spaces between the several pairs of feed rolls. The forming roll is carried by a shaft 51, which is journaled in bearing blocks 52, mounted for sliding adjustment within inclined recesses 53 formed in the sides of the frame. Adjustment of the blocks 52, and consequently of the forming roll, is effected by means of adjusting screws 54, having a threaded connection with inclined sockets 55 secured to the frame, said screws having their lower ends swivelled to the blocks 52.

For operating the screws 54, miter gears 56 are secured to their upper ends, and are in mesh with similar gears 57 secured on a transverse shaft 58 which is journaled in the sides of the frame, and provided at one end with a hand wheel 59 or other suitable means for rotating the same. For driving the forming roll, a sprocket wheel 60 is secured to each end of the shaft 51, and these sprocket wheels are connected by sprocket chains 61 to sprocket wheels 62 secured to the ends of the shaft 44.

Cooperating with the roll 50 is a former, the construction of which may be varied somewhat in accordance with the kind of work to be performed. The type of former shown in Figures 1 to 7 is especially adapted for working upon strips of moderate thickness, as for example, a chair back or table rim. It comprises one or more pieces of curved sheet iron or steel 63, adapted to be arranged in alinement, each with its concave side toward the roll 50 and supported by a yoke 64. The front end of each strip 63 is bent downwardly, and clamped between the front face of the yoke and a fulcrum block which is secured by means of a set screw 66 or the like. The rear end of the strip 63 is bent downwardly and secured by a bolt 67 to the flat face of a cam 68, which is mounted to rock on a pin 69 secured between two ears 70 extending rearwardly from the yoke 64. The cam 68 has a downwardly extending arm 71, by means of which the cam may be rocked about the pin 69 to vary the curvature of the steel strip 63. The means for adjusting the cam 68 and the curvature of the steel strip includes a screw 72, provided with a hand wheel 73 and threaded into a block 74, which is mounted on pins 75 in an upstanding projection 76. The front end of the screw 72 has a swivelled connection with a block 77, which is mounted on pins 78 within a recess in the lower end of the cam arm 71. Thus, by rotating the hand wheel 73, the cam 68 may be rocked, and the steel strip 63 stretched to increase its radius, or relaxed to decrease the same.

The intermediate portion of the steel strip 63 is pressed against the wood strip, not only by its own resiliency but by a pressure bar 79 extending transversely across its underside and secured to the upper ends of stems 80, which are slidably mounted in the yoke 64, and constantly urged upwardly by expansile coiled springs 81, which surround the stems within a recess 82 extending transversely through the central part of the yoke.

In addition to the means for adjusting the curvature of the steel springs 63, provision is also made for adjusting the yokes 64 bodily toward or away from the pressure roll 50, in order to adapt the former for

strips of different thickness. For this purpose each fulcrum block 65 is provided on the under side of its forward end with a transverse groove 83, which receives the 5 upper edge of an angle bar 84, thus forming a fulcrum about which the yoke has a rocking adjustment. The angle bar 84 is rigidly secured to brackets 85 supported by the frame 10. The rear end of the yoke is adjustably supported by a plurality of adjusting screws 86, threaded into an angle bar or bracket 87 extending transversely across the rear side of the frame. As shown 10 in Figure 3, a plurality of screws 86 are provided for each yoke so that they may be aligned laterally with each other, and the screws of each yoke are connected by a series of small pinions 88 so as to rotate in unison, one of the pinions being secured 15 to a spindle 88^a which is provided with a hand wheel 89.

In the former shown in Figures 8 to 11, the yoke 64^a is adjusted by a means of screws 86 in the same manner as the yoke 64, and 20 is provided on its upper face with a strip 63^a which is clamped at its front end to the front face of the yoke by a fulcrum block 65 in the same manner as the strip 63, but the rear end of the strip 63^a is secured to a 25 block 102 having forwardly projecting pins, which are slidably mounted in longitudinal bores 103 in the yoke 64^a. The block 102 also has a threaded bore which receives a 30 threaded spindle 104 having its front swivelled in a block 105, which is secured within a recess 106 at the rear end of the yoke, and the spindle is rotated by means of a 35 hand wheel 107 at its rear end to advance or retract the block 102, so as to adjust the 40 tension of the strip 63^a. This former has no pressure bar 79 as is used in connection with the yoke 64, and is especially adapted for bending thin strips.

Interchangeable with the two formers heretofore described is a third former, 45 shown in Figure 12, which is especially adapted for bending extra heavy material such as rockers or wheel rims. This former is made of a single casting 64^b, which is 50 vertically adjustable by means of screws 86 in the same manner as the yokes 64 and 64^a, but both the pressure bar 79 and the spring strip 63 are eliminated, and the forwardly projecting fulcrum block 65^b having 55 a transverse groove 83^a for receiving the angle bar 84 is an integral part of the casting.

As heretofore stated, provision is made 60 for applying both heat and pressure to the strip during the bending operation. In order that the heat may thoroughly permeate the wood and produce the desired physical effect thereon, provision is made for applying heat through each of the rolls 16, 17, 25, 65 26 and 50. In order to supply heat con-

tinuously by means of the rolls, each roll is in the form of a cylindrical shell heated by gas from within. The detailed construction by means of which the heat is supplied is best illustrated in connection with roll 50, 70 in Figures 2 and 3. As shown, each end of the roll has a head 90 with an inwardly extended boss 91, which supports a hollow inner drum 92 surrounding the shaft 51, and spaced therefrom and having numerous 75 small perforations 93, which form a gas burner. Gas is supplied to this burner through a passageway 94 extending centrally through one end of the shaft 51, and having an outlet within the drum 92. The 80 outer end of the passageway 94 is adapted to be connected with the discharge end of a gas supply pipe 95, and is also provided with a suitable air valve 96. Thus, it will be seen that gas may be continuously supplied 85 to the burner 92 and burned during the operation of the roll. Suitable openings 97 are provided in the ends of the roll for the discharge of the products of combustion. Each of the rolls 16, 17, 25 and 26 is provided with similar means for supplying heat 90 to the wood strip.

At the rear end of the machine, a bracket 98 is adjustably secured to the frame by means of screws 99 or the like, and this 95 bracket has a plurality of pairs of eccentrics 100 adjustably mounted therein, and carrying rolls 101 between which the wood strip is fed after passing through the former, so as to hold the strip in uniformly 100 bent position until it is sufficiently cool to maintain its shape permanently.

As explained in the foregoing description, in adjusting the machine to strips of different thickness, the gears 41 are swung 105 forwardly out of mesh with the gears 29 by rotating the hand wheels 49. The rolls 25 and 26 may then be adjusted as a unit by a rotation of the hand wheels 40. When the desired adjustment is obtained, the 110 gears 41 are swung back into mesh with the gears 29. Each yoke 64 may be swung about its fulcrum toward or from the roll 50 by turning its hand wheel 89. The curvature of the steel strips 63 may be 115 adjusted according to the amount of bend to be imparted to the strip by means of the hand wheel 73. After the machine has been properly adjusted, the strips are fed between the feed rolls 16, 17 and 25, 26, and 120 the entire bending operation takes place automatically.

In carrying out the process of bending, according to the method above described, 125 dry heat alone is applied to the wood through the medium of the rolls 16, 17, 25, 26 and 50. The wood is thoroughly heated both before and during the bending operation, and a permanent bend is imparted without the use of any moisture. Both the 130

time and expense of moistening and drying the wood, as well as the damage which is likely to be caused thereby, is avoided.

While I have shown and described the specific details of construction of a machine which is well adapted for carrying out the invention, it is to be understood that this is merely illustrative, and that many modifications may be made in the size, shape and relative arrangement of the various parts thereof without departing from the salient features of the invention or sacrificing any of the advantages thereof.

What is claimed is:

15 1. In a wood bending machine, the combination of a pressure roll, a concave former cooperating therewith, feed rolls in front of the pressure roll and former, certain of said rolls being hollow and having an inner perforated drum forming a gas burner, and means for supplying gas to said burner.

20 2. In a wood bending machine, the combination of a pressure roll, a concave former cooperating therewith, pairs of feed rolls in front of the pressure roll and former, a pair of blocks in which the upper one of each pair of feed rolls is journaled, gears connecting said feed rolls and also journaled in said blocks, means for simultaneously adjusting said blocks vertically to adjust all of the upper feed rolls as a unit, and means for driving all of said rolls in unison.

25 3. In a wood bending machine, the combination of a pair of cooperating bending members, pairs of feed rolls in front of the same, each provided with a driving gear at each end, a pair of blocks in which the ends of the upper feed rolls are journaled, intermediate gears connecting the upper feed rolls and also journaled in said blocks, means for simultaneously adjusting the blocks vertically to adjust all of said upper feed rolls as a unit, means including gears connecting the front upper feed roll with the front lower feed roll, blocks in which the last named gears are mounted, said last named blocks being adjustable horizontally to temporarily disconnect the upper from the lower rolls while the upper rolls are adjusted vertically.

40 4. In a wood bending machine, the combination of a pressure roll, a former having a concave surface cooperating with the pressure roll, pairs of feed rolls in front of the pressure roll and former, a pair of blocks in which the upper one of each pair of feed rolls is journaled, gears connecting the upper feed rolls and also supported by said blocks, means for simultaneously adjusting said blocks vertically to adjust all of said upper feed rolls as a unit, said pressure roll and each of the feed rolls being hollow and having an inner perforated

drum forming a gas burner, means for supplying gas to said burner, and means for driving all of said rolls in unison.

5. In a wood bending machine, the combination of a pair of cooperating bending members, pairs of feed rolls in front of the same, a pair of blocks in which the ends of the upper feed rolls are journaled, gears also mounted in said blocks and connecting the upper feed rolls, means for adjusting said blocks vertically to adjust all of said upper feed rolls as a unit, means including gears connecting the upper front feed roll with the lower front feed roll, blocks in which the last named gears are mounted, said last named blocks being adjustable horizontally to temporarily disconnect the upper from the lower rolls while the upper rolls are adjusted vertically, each of said rolls being hollow and having an inner perforated drum spaced from the outer shell of the roll and forming a gas burner, and means for supplying gas to said burner during the rotation of the roll.

6. In a wood bending machine, a transversely disposed pressure roll, a longitudinally extending former having a flexible strip with a concave face cooperating with the roll, said former being fulcrumed at one end, means for adjusting the other end of the former to move the flexible strip toward or away from the pressure roll to accommodate wood strips of different thickness, and means for varying the distance between the ends of the flexible strip to vary the curvature of said strip.

7. In a wood bending machine, a pressure roll, a former having a concave cylindrical face cooperating therewith, said former being fulcrumed at one end, means for adjusting the other end of the former to move its concave face toward or away from the pressure roll, and means for adjusting the curvature of the concave face.

8. In a wood bending machine, a pressure roll, a former having a concave cylindrical face cooperating therewith, means for adjusting the former toward or away from the roll, and means for varying the curvature of said concave face.

9. In a wood bending machine, the combination of a pressure roll, a longitudinally curved flexible strip, means at the ends of the strip for supporting the same transversely to the roll with its concave face toward the roll, means for feeding strips of wood between the roll and said curved strip, and means for adjusting one of said supports to vary the distance between the ends of the curved strip, thereby varying its curvature.

10. In a wood bending machine, the combination of a pressure roll, a former cooperating therewith and including a yoke, a curved pressure strip secured at one end

to the yoke, and a cam to which the other end of the pressure strip is secured, and means to rock said cam to vary the distance between the ends of the strip and thereby 5 vary the curvature of the strip.

11. In a wood bending machine, the combination of a pressure roll, a former cooperating therewith and including a yoke, a curved metallic pressure strip secured at 10 one end of the yoke, a cam about which the other end of the pressure strip is bent, means to rock said cam to stretch or relax said strip and thus vary the curvature thereof, and means for adjusting the yoke 15 to move the strip bodily toward or away from the roll.

12. In a wood bending machine, the combination of a pressure roll, a yoke fulcrumed adjacent the roll, means for adjusting the yoke about its fulcrum toward and away from the roll, a metallic pressure strip carried by the yoke and having a concave cylindrical surface cooperating with the roll, a bar supported in contact with the convex 25 face of the strip, and means causing the bar to exert pressure against the strip.

13. In a wood bending machine, the combination of a pressure roll, a yoke mounted adjacent the roll and adjustable toward and 30 away from the roll, a pressure strip carried by the yoke and having a concave cylindrical surface cooperating with the roll, a bar supported in contact with the convex face of the strip, resilient means for causing the 35 bar to exert pressure against the strip, and means for adjusting the distance between the ends of the strip to vary the curvature thereof.

14. In a wood bending machine, the combination of a pressure roll, a yoke fulcrumed adjacent the roll, means for adjusting the yoke about its fulcrum toward and away from the roll, a curved pressure strip secured at one end to the yoke, a cam

mounted for rocking movement in the yoke 45 and having the other end of the pressure strip bent about the same and secured thereto, means to rock the cam to vary the curvature of the strip, a bar supported in contact with the convex face of the strip, 50 and resilient means causing the bar to exert pressure against the strip.

15. In a wood bending machine, the combination of a pressure roll, a former cooperating therewith, a series of feed rolls in 55 advance of the pressure rolls, said pressure rolls and each of the feed rolls being hollow, and means for supplying heat and pressure to said rolls.

16. In a wood bending machine, the combination with a pressure roll, a former cooperating therewith, a series of pairs of upper and lower feed rolls in front of the pressure roll, and means for adjusting all of said upper feed rolls as a unit, and 60 means for driving all of said rolls in unison.

17. In a wood bending machine, the combination of a pair of cooperating bending members, pairs of upper and lower feed 70 rolls in front of the same, a pair of blocks in which the ends of the upper feed rolls are journaled, gears also mounted in said blocks and connecting the upper feed rolls, means for adjusting said blocks vertically 75 to adjust all of said upper feed rolls as a unit, means including gears connecting the upper front feed roll with the lower front feed roll, blocks in which the last named gears are mounted, said last named blocks 80 being adjustable horizontally to temporarily disconnect the upper from the lower rolls while the upper rolls are adjusted vertically.

In testimony, that I claim the foregoing 85 as my own, I have hereto affixed my signature.

LORENZO JOHNSON.
